UNITED STATES PATENT OFFICE.

MIKE TELESZKY, OF JENNERS, PENNSYLVANIA.

CARTRIDGE.

1,278,786.

Specification of Letters Patent. Patented Sept. 10, 1918.

Application filed December 26, 1917. Serial No. 208,819.

To all whom it may concern:

Be it known that I, MIKE TELESZKY, a subject of the King of Hungary, residing at Jenners, in the county of Somerset and State 5 of Pennsylvania, have invented certain new and useful Improvements in Cartridges, of which the following is a specification.

The primary object of this invention is the provision of a cartridge having a projectile 10 adapted for traveling through the water and provided with an automatically adjustable steering means for maintaining the projectile in a straight course.

A further object of the device is the provision of a projectile adapted to be fired 15 into the water and arranged to be steered in a straight line of travel toward the objective point at which the projectile is fired, the device being easy and inexpensive to 20 manufacture and presenting the general form of a cartridge before being fired.

With these general objects in view and others that will appear as the nature of the invention is better understood, the same consists in the novel construction, combination 25 and arrangement of parts hereinafter more fully described.

In the drawings forming a part of this application, and in which like reference characters refer to corresponding parts throughout the several views,

Figure 1 is a central longitudinal sectional view taken through the device.

Fig. 2 is a similar view of the bullet with 35 its rudder positioned in operative arrangement.

Figs. 3 and 4 are transverse sectional views taken upon lines III—III and IV—IV of Fig. 2 and

Fig. 5 is a detail sectional view of the rudder.

Referring more in detail to the drawings, the device includes a shell 10 having a bullet 11 projecting therefrom while a fulminating cap 12 is provided in the base or 45 closed end 13 of the shell.

The bullet 11 is of tubular formation having an axial bore 14, a disk 15 being seated within an annular socket 16 at the rear end 50 of the bullet and thereby forming a check for the explosive material 17, such as dynamite arranged within the shell 10 between the end 13 thereof and the said bullet and disk.

55 A rubber 18 is normally arranged within the bore 14 having a rod 19 positioned

axially of the bore and provided with a cross head 20 having its opposite ends slidably positioned within opposite longitudinal grooves 21 in the sides of the bore 14. The 60 steering member or head 22 that is upon the end of the rod 19 opposite the cross piece 20, is provided with a plurality of radially projecting triangular shaped fins 23 thereby giving the appearance of the steering head 65 somewhat the shape of a cone.

The projectile being adapted for firing in the water at submerged objects, it will be seen that upon exploding the charge 17, the bullet 11 and disk 15 will be projected forwardly into the water, and the force of the water passing through the bore 14 will immediately remove the disk 15 from the socket 16 and will also rearwardly position the rudder 18 in its operative arrangement as indicated in Fig. 2 of the drawing. Shoulders 24 are arranged at the rear ends of the grooves 21 forming stops against which the cross piece 20 of the rudder is seated at the extreme rearward movement of the rudder, 75 thereby preventing the rudder from becoming separated from the bullet 11. The continued forward movement of the bullet will be directed in a straight course by means of the fins 23 of the rudder. It will be noted 80 that the cross piece 20 is rectangular in cross section for maintaining the rod 19 in axial alignment with the bullet 11 during the rearward movement of the rudder as well as during the steering operation, the rudder 85 being maintained within the bore 14 prior to the firing of the projectile by means of wax 90 arranged in the outer ends of the groove 21 if found desirable.

A cartridge is provided by which a bullet 95 may be shot and steered in a straight course through the water, the bullet 11 having a tapered portion 26 terminating at the forward end of the bore 14 and presenting little obstruction to the passage of the bullet 100 through the water.

What I claim as new is:—

1. A cartridge comprising a shell, a bullet provided with an axial bore and a socket in its rear end normally positioned within the shell, a disk temporarily arranged within the socket, explosive material within the shell rearwardly of said disk and bullet, the said bullet being arranged with opposite longitudinal grooves within the bore thereof, 105 a rudder positioned within said bore before the device is fired including a cross piece 110

slidably arranged within the said grooves, a rod carried by the cross piece and a finned steering head at the free end of the rod adapted for positioning rearwardly of the bullet in its operative arrangement after the firing of the device.

5 2. A cartridge comprising a shell, explosive material within the shell, a tubular bullet removably projecting into the shell
10 seated against the said explosive and having a forwardly tapered end, the interior of the bullet being provided with opposite longitudinal grooves, a squared cross piece slidably arranged within the said grooves, re-

taining means in the outer ends of the 15 grooves and stop shoulders at the inner ends thereof arranged within the path of movement of the said cross piece, a rod carried by the cross piece and a head at the free end of the rod provided with a plurality of 20 radially projecting fins of triangular formation, the said head being positioned rearwardly of the bullet during the passage of the latter through the water with the cross piece in contact with the said shoulders.

25

In testimony whereof I affix my signature.

MIKE TELESZKY.
